CLAIM

(22) Filed: **Oct. 23, 2014**

The ornamental design for a universal serial bus (USB) electrical wiring device, as shown and described.

DESCRIPTION

Related U.S. Application Data

(62) Division of application No. 29/427,806, filed on Jul. 23, 2012.

FIG. 1 is a front view illustrating the USB electrical wiring device, the device includes a first single USB port opening and a second single USB port opening disposed at one end portion thereof, and a paddle switch handle disposed at the opposite end thereof, with broken lines depicting unclaimed subject matter that forms no part of the claimed design; FIG. 2 is an isometric view of the USB electrical wiring device depicted in FIG. 1, with broken lines depicting unclaimed subject matter that forms no part of the claimed design;

(51) **LOC (10) Cl.** 09-03

FIG. 3 is a first side view of the USB electrical wiring devices depicted in FIG. 1, the opposite side view of the USB electrical wiring device being a mirror image of the first side view and thus omitted for the sake of brevity, with broken lines depicting unclaimed subject matter that forms no part of the claimed design;

(52) **U.S. Cl.**

FIG. 4 is a first end view of the USB electrical wiring device depicted in FIG. 1, with broken lines depicting unclaimed subject matter that forms no part of the claimed design; and, FIG. 5 is a second end view of the USB electrical wiring device depicted in FIG. 1, with broken lines depicting unclaimed subject matter that forms no part of the claimed design.
